UNITED STATES PATENT OFFICE

2,097,858

BOX FOR DISPENSING TISSUES

Sol Herz, New York, N. Y., assignor to Federated Mills, Inc., New York, N. Y., a corporation of New York

Application September 15, 1936, Serial No. 100,823

1 Claim. (Cl. 229—17)

My invention relates to a container for holding, protecting and dispensing a package of folded sheets of tissue or other papers which are arranged so that removing one sheet will expose 5 the edge of the next one below it.

It is the purpose of the present invention to provide a container which is formed of a single blank and comprises a top portion enclosed within a continuous weakened line, whereby said portion may be readily removed to form an opening 10 in the top panel.

Another object of the present invention is to provide the sides of the container with windows, consisting of openings covered with a transparent material, whereby the contents are visibly 15 displayed.

A still further object of my invention is to provide a rigid support for the top panel, withstands the strain exerted upon the latter when 20 the removable blank is separated along said weakened line, as the sidewalls weakened on account of the extensive window cutouts are unable to take up said strain.

I accomplish these objects by means of the 25 construction and arrangement of parts described in the following specification set forth in the appended claim and illustratively exemplified in the accompanying drawing in which:

Figure 1 is a perspective view of my improved 30 container showing a portion of the outer layer of the cover or top broken away to show the blank in the inner layer before removal.

Figure 2 is a substantially longitudinal sectional view of the container taken on lines 2—2 35 of Figure 1.

Figure 3 is a substantially transverse sectional view taken on lines 3—3 of Figure 1.

Figure 4 is a plan view of the blank from 40 which the container is formed.

Referring now to the drawing, the container 45 comprises a single piece of material, preferably cardboard, cut and folded to form a box having a bottom 10, two sides 11, and a top 13.

The sides 11 are provided with extensive cut- 50 out portions forming windows 14, which are covered by sheets of transparent material 15, the marginal portions of which are adhered to the inner surface of the side walls marginally of the windows 14.

The top 13 of the container is formed by a 55 panel of the material integral along one edge with one side 11 and is provided with a center blank 16, which is outlined by a continuous perforated line 17, and which is removable from the top by merely separating the blank along the

perforated line. A second panel or cover piece 18 for the top 13 is provided by including an integral portion of material at the outer edge of the second side 11, which piece is the same size as that of the top 13 and is folded over onto the latter to conceal the same and the blank 16. When the complete package is dispensed the cover piece 18 is adhered to the top 13 by utilizing spots 19 of adhesive, but after the package has been broken and the blank 16 removed, the outer or 10 free corners of the cover piece 18 are inserted in slots 20 cut into the corresponding corners of the underlying top 13, as illustrated in Figures 1 and 4.

The contents of the box have not been illustrated, but it will be readily appreciated that upon removal of the blank 16 an opening can be provided in the top 13 and that the contents may be removed through the opening, which is closed by the cover 18.

The blank from which the container is folded is illustrated in Figure 4 and consists of five panels set off from each other by lines of scoring 21 to form the top 13, side 11, bottom 10, second side 11 and cover piece 18. The top 13 has a narrow strip 22 along its outer edge to be folded down and adhered to the upper marginal portion of the second side 11, see Figure 2. The top 13 and bottom 10 are provided with projecting portions 23 which fold upright to overlap each other and to form the end walls, each of the projections 23 having the full size of an end wall. The sides 11 are also provided with projecting pieces 24 at their ends, each of said pieces 24 having half the size of an end wall and being sandwiched between the projections 23 of the top and bottom sections when the box or container is assembled.

This arrangement makes the end walls and the connection between the individual sections 40 sufficiently rigid to take up the strain exerted upon the top and the weakened side walls when the removable blank is separated along said perforated line by being lowered over the top 13 and its corners inserted in the slots 20 of the latter. 45

Having described my invention and the manner in which the same may be used, what I claim and desire to secure by Letters Patent is:

A dispensing container of rectangular form comprising a top panel having a center portion 50 enclosed within a continuous weakened line to permit easy removal of said portion in order to form an opening in said top panel, two side walls opposite each other, said side walls being substantially weakened by extensive window cut- 55

outs, said container being folded from a blank having four mid-portion sections to form the bottom, side walls and top, the bottom and the top having end flaps on either side thereof, each of said flaps having the full size of an end wall and being folded inwardly to overlap the corresponding flap of the opposite section, the side wall sections having on either side flaps of half

the size of an end wall, said side wall flaps being folded inwardly and sandwiched between the flaps of the top and the bottom section, whereby the endwalls become sufficiently rigid to take up the strain exerted upon the top and the weakened side walls when said removable portion in the top is separated along said weakened line. 5
